SAMPLING DEVICE

Sidney J. Robison, New York, N. Y., assignor to
 Universal Atlas Cement Company, a corpora-
 tion of Indiana

Application April 30, 1943, Serial No. 485,251

5 Claims. (Cl. 73—422)

This invention relates to a sampling device for sampling material which is carried at a high velocity by compressed air pressure through a duct. Cement is often transported by this method and it is sometimes necessary to obtain samples of the cement while flowing through the duct. Since cement is a very fine material, the sampling devices now in common use are not suitable for obtaining the samples.

It is an object of my invention to provide a sampling device for obtaining samples of cement as it flows through a duct under pressure.

This and other objects will be more apparent after referring to the following specification and attached drawing in which the single figure is a sectional elevation of the sampling device.

Referring more particularly to the drawing, the reference numeral 2 indicates a duct through which cement is being carried by compressed air pressure. Welded to the duct 2 is an air tight box 4 to which is attached a detachable sample container 6. The box 4 is fitted with a valve 8. A sampling tube 10 passes through the box 4 and slides in a metal guide 12 welded to the duct 2 and also through a packed gland or guide 14 welded to the box 4. The top of the tube 10 is closed by means of a plug 16 and a second plug 18 is inserted in the tube 10 some distance from the end thereof, thus forming a passageway 20 having an inlet 22 below the plug 16 and an outlet 24 above the plug 18. A spring 24 surrounds the lower end of the tube 10 and tends to hold the tube in a retracted position by exerting pressure on an abutment 34 attached thereto. The tube 10 is raised and lowered by a connecting rod 26 which is actuated by a cam 28 driven by a motor 30 through a speed reducer 32.

The operation of the device is as follows:

In its normal or retracted position, the top of the tube 10 is flush with the upper surface of guide 12. When it is desired to obtain a sample of cement, the motor 30 is actuated to rotate the cam 28, thus raising the connecting rod 26 and compressing the spring 24 between an abutment 36 on the guide 14 and the abutment 34 fastened to the tube 10. The valve 8 is opened to permit a certain amount of air to escape from the sampling container 4 so that there will be a flow of air and material through the sampling tube. By varying the amount of air escaping from the container 4, the pressure inside the sampling tube is changed, thus controlling the rate of flow of the air through the sampling tube and the amount of cement drawn from the duct

2 at each stroke of the sampler. The motor 30 is then actuated to lower the tube 10 into retracted position, the spring 24 forcing the tube downwardly as the cam 28 rotates. The sample container 6 is detached from the box 4 and a new sample container 6 substituted therefor. If desired, the motor 30 may be controlled by a timing switch which will operate at predetermined intervals to thrust the tube 10 upwardly into the

10 stream of the material flowing from the duct 2 and to retract it to its normal position.

While one embodiment of the invention has been shown and described, it will be apparent that other adaptations and modifications may be made without departing from the scope of the attached claims.

I claim:

1. A device for sampling material carried by air pressure in a duct comprising a sealed box 20 attached to said duct, said duct having an opening therein, a guide fastened to said duct, a guide attached to said box, a sampling tube mounted in said guides extending through the box from the exterior thereof and movable through the 25 opening in the duct and having a passageway placing the duct and box in communication with each other when the tube is extended into the duct, means for moving said tube into and out of said duct, and means for permitting air to 30 escape from said box to cause flow of said material from said duct through said tube into said box when the sampling tube is in communication with said duct.

2. A device for sampling material carried by air pressure in a duct comprising a sealed box attached to said duct, said duct having an opening therein, a guide fastened to said duct, a guide attached to said box, a sampling tube mounted in said guides extending through the box from the exterior thereof and movable through said 40 opening, said tube having a passageway with an inlet in communication with said duct and an outlet in communication with said box when the tube is extended into the duct, means for moving said tube into and out of said duct, and means for permitting air to escape from said box to cause flow of said material from said duct through said passageway into said box when the inlet of said passageway is in communication 45 with said duct.

3. A device for sampling material carried by air pressure in a duct comprising a sealed box attached to said duct, said duct having an opening therein, a container for the sample detachably mounted on said box, a guide fastened to

said duct, a guide attached to said box, a sampling tube mounted in said guides extending through the box from the exterior thereof and movable through said opening, said tube having a passageway with an inlet in communication with said duct and an outlet in communication with said box when the tube is extended into the duct, means for moving said tube into and out of said duct, and a valve for permitting air to escape from said box to cause flow of said material from said duct through said passageway into said box when the inlet of said passageway is in communication with said duct.

4. A device for sampling material carried by air pressure in a duct comprising a sealed box connected to said duct, said duct having an opening therein communicating with said box, a sampling tube in said box movable through said opening and having a passageway which places the duct and box in communication with each other when the tube is extended into the duct, means controlled from outside the box for moving said tube into and out of said duct, and

means for permitting air to escape from said box to cause flow of material from said duct through said tube into said box when the sampling tube is in communication with said duct.

5. A device for sampling material carried by air pressure in a duct comprising a sealed box connected to said duct, said duct having an opening therein communicating with said box, a container for said sample detachably mounted on said box, a sampling tube in said box movable through said opening and having a passageway which places the duct and box in communication with each other when the tube is extended into the duct, means controlled from outside the box for moving said tube into and out of said duct, and means for permitting air to escape from said box to cause flow of material from said duct through said tube into said box when the sampling tube is in communication with said duct.

SIDNEY J. ROBISON.
